TOY

Robert K. Ostrander, South Orange, N. J., assignor to Badger Cut Outs, Inc., Maspeth, Long Island, N. Y., a corporation of New York

Application November 9, 1943, Serial No. 509,548

6 Claims. (Cl. 46—146)

This invention relates to toys and pertains particularly to toys of a type known as "jack in the box."

It is an object of the invention to provide a toy of this type which can be made entirely of heavy paper or cardboard, without the use of the customary metal springs, thus making possible a very inexpensive construction of a type of toy which is very popular with small children.

Other objects and advantages of the invention will appear hereinafter.

A preferred embodiment of the invention selected for purposes of illustration is shown in the accompanying drawings, in which,

Figure 1 is a plan view of one of the elements of the lazy tong assembly.

Figure 2 is a plan view of the other element.

Figure 3 is a side elevation of the toy showing the box opened and the lazy tong assembly in expanded condition.

Figure 4 is a similar view showing the box closed and the lazy tong assembly in compressed condition, and

Figure 5 is a perspective view similar to Figure 3.

Referring to the drawings, the toy comprises a resilient lazy tong assembly consisting of two elongated strips of heavy paper or cardboard designated by the numerals 1 and 2. The strip 1 carries on its upper end an enlarged panel 3 which may be shaped and decorated in the form of any desired face or figure. The panel 3 is preferably integral with the strip 1 and is hinged thereto by a transverse fold line 4. The remainder of the strip is divided into a series of smaller panels 5 by transverse fold lines 6, the successive fold lines being folded in opposite directions to provide a zig-zag conformation. The end panel 7 at the bottom of the strip is shaped in the form of a tab for purposes hereinafter set forth.

The strip 2 is likewise divided into a series of small panels 8 by transverse fold lines 9, the successive fold lines being likewise folded in opposite directions to form a zig-zag conformation, but the top end panel 10 is formed in the shape of a tab for purposes hereinafter set forth. The strip 2 carries on its lower end an enlarged panel 11, preferably integral with the strip 2, and is hinged thereto by the transverse fold line 12.

The opposed edges of the strips 1 and 2 are provided with matching slots 13 extending inwardly from the respective edges of the strip to the median lines thereof, whereby the two strips may be assembled in overlapping relation by meshing the opposed slots to form a lazy

tong structure of surprising resilience. In assembling the strips, the tab 10 is inserted through the slot 14 in the strip 1 and the tab 7 is inserted in the slot 15 in the panel 11, thus holding the strips in properly assembled relationship.

The panel 11 serves as a bottom for the box 16 which may be of any desired construction. However, for purposes of economy in construction and packing, I prefer to form the box of a single piece of heavy paper or cardboard, having fold lines 17 defining the side panels of the box, and having a separate fold line 18 defining a lid 19. If desired, the bottom panel 11 may be provided with tabs 20 fitting into slots 21 in the side panels of the box to hold the bottom panel in position.

After the toy is assembled, the lazy tong strip assembly may be compressed until the lid of the box can be closed as shown in Figure 4. Upon releasing the lid, the compression in the lazy tong strip assembly is sufficient to flip open the lid and to cause the end panel 3 to be projected some distance beyond the confines of the box.

It will be understood that the invention may be variously modified and embodied within the scope of the subjoined claims.

I claim as my invention:

1. A toy comprising, in combination, a box, said box having a bottom and a hinged lid, and a resilient lazy tong assembly mounted within said box and confined under compression between said bottom and said lid, and adapted on release of said lid to expand to project the upper end thereof beyond the confines of the box.
2. A toy comprising, in combination, a box, said box having a bottom and a hinged lid, and a resilient lazy tong assembly mounted within said box and confined under compression between said bottom and said lid, and adapted on release of said lid to expand to project the upper end thereof beyond the confines of the box, said assembly comprising two strips of cardboard, each having a plurality of transverse fold lines with the successive fold lines of each strip folded in opposite directions.
3. A toy comprising, in combination, a box, said box having a bottom and a hinged lid, and a resilient lazy tong assembly mounted within said box and confined under compression between said bottom and said lid, and adapted on release of said lid to expand to project the upper end thereof beyond the confines of the box, said assembly comprising two strips of cardboard having oppositely disposed edge slots meshed together, and said strips being folded to provide a zig-zag conformation.

4. A toy comprising, in combination, a box, said box having a bottom and a hinged lid, and a resilient lazy tong assembly mounted within said box and confined under compression between said bottom and said lid, and adapted on release of said lid to expand to project the upper end thereof beyond the confines of the box, said assembly comprising two strips of cardboard, each having a plurality of transverse fold lines with the successive fold lines of each strip folded in opposite directions, the upper end of one of said strips having a tab formed therein, and the other of said strips having a slot to receive said tab.

5. A toy comprising, in combination, a box, said box having a bottom and a hinged lid, and a resilient lazy tong assembly mounted within said box and confined under compression between said bottom and said lid, and adapted on release of said lid to expand to project the upper end thereof beyond the confines of the box, said assembly comprising two strips of cardboard, each having a plurality of transverse fold lines with the successive fold lines of each strip folded in opposite directions, the upper end of one of

said strips having a tab formed therein, and the other of said strips having a slot to receive said tab, the lower end of one of said strips terminating in an enlarged panel constituting a bottom for said box, said panel having a slot therein, the lower end of the other of said strips having a tab formed therein for insertion in said slot.

6. A toy comprising, in combination, a box, said box having a bottom and a hinged lid, and a resilient lazy tong assembly mounted within said box and confined under compression between said bottom and said lid, and adapted on release of said lid to expand to project the upper end thereof beyond the confines of the box, said assembly comprising two strips of cardboard having oppositely disposed edge slots meshed together, and said strips being folded to provide a zig-zag conformation, the lower end of one of said strips terminating in an enlarged panel constituting a bottom for said box, said panel having a slot therein, the lower end of the other of said strips having a tab formed therein for insertion in said slot.

ROBERT K. OSTRANDER.
